No. 675,668.

Patented June 4, 1901.

F. C. NEWELL.
ELECTRIC BRAKE.

(Application filed Apr. 28, 1900.)

(No Model.)

UNITED STATES PATENT OFFICE.

FRANK C. NEWELL, OF WILKINSBURG, PENNSYLVANIA, ASSIGNOR TO THE WESTINGHOUSE AIR BRAKE COMPANY, OF PITTSBURG, PENNSYLVANIA.

ELECTRIC BRAKE.

SPECIFICATION forming part of Letters Patent No. 675,668, dated June 4, 1901.

Application filed April 28, 1900. Serial No. 14,685. (No model.)

To all whom it may concern:

Be it known that I, FRANK C. NEWELL, a citizen of the United States, residing at Wilkinsburg, county of Allegheny, State of Pennsylvania, have invented or discovered a certain new and useful Improvement in Electric Brakes, of which improvement the following is a specification.

The object of my invention is to provide an improvement in brakes for electrically-propelled railway-cars; and to this end it consists in a new and improved braking system comprising means whereby the current-supply from the main line to the running controller at either end of a car may be cut off and a local braking-circuit connected up by the movement of a single braking-switch, which is operative from either end of a car, and whereby on movement of the single braking-switch the running controller at either end of the car is adapted to control the braking-current by the same means as are employed to control the current to the motors when running.

My invention provides means whereby the brakes may be quickly applied from either end of the car by a single movement of one braking-switch, and by this movement of the braking-switch the running controller at either end of the car is so connected with the local braking-circuit that either controller may be operated to vary the resistance. Ordinarily but one of the running controllers would be employed for this purpose—that is, the controller at the front end of the car—the other usually being left locked or without an operating-handle; but if under any circumstances it may be necessary or desirable to have both controllers in condition to permit a variation of the resistance and a corresponding variation in the braking-current from both the front and rear platforms this may be done.

In the construction shown in the drawings the movement of the braking-switch to the braking position cuts off the supply of current from the main line to both running controllers and applies the brakes no matter what the position of either controller may be, any variation in the position of the running con-

troller affecting only the resistance in the braking-circuit.

In the accompanying drawings, which illustrate an application of my invention, Figure 1 is a diagram showing the running controllers and reversing-switches in open position, the leads and connections for running and braking, and the braking-switch in the position which it will occupy when the brakes are off; Fig. 2, a view showing the braking-switch in position for braking, and Fig. 3 a plan view of the mechanism by which the braking-switch may be operated from either end of the car.

In the application of my invention shown in the drawings I employ a braking-switch B, preferably located about midway between the ends of a car which is equipped with a running controller C and a reversing-switch D at each end. When the reversing-switch at either end of the car is in position for running ahead, the controller-bars 1 2 3 4 are in contact with the terminal points F² AA², &c., on the left, and when it is in position for backing the points 5 to 12 on the right are in contact with the terminal points F² AA², &c. With the braking-switch in the position shown in Fig. 1, if either controller C be moved so as to cause the contact-bars 13 14 to make contact with the points TC and R' current will flow through the trolley T to the point TL on the braking-switch, through the bar 28, lead TC, contact-bars 13 14 on the running controller, lead R', resistance device R, leads R⁵ and 19, contact-bar 4 on the reversing-switch, lead A', armature A of No. 1 motor, lead AA', contact-bar 3 on the reversing-switch, leads F' and F' C, contact-bar 30 on the braking-switch, lead F' M, through the field of No. 1 motor, lead E' M, contact-bar 34 on the braking-switch, lead E' C, contact-bars 20 and 19 on running controller, lead 15, contact-bar 2 on reversing-switch, lead A², armature of No. 2 motor, lead AA², contact-bar 1 on reversing-switch, leads F² and F² C, contact-bar 31 on braking-switch, lead F² M, field of motor No. 2, and to ground. To apply the brakes, the braking-switch is moved to the position shown in Fig. 2, by which movement the supply of current to the controllers is cut off and the motors are con-

connected in a local braking-circuit, to which they supply current as the armatures continue to revolve. When the motors are acting as generators, the current from the armatures will flow in the direction indicated by the dotted arrows. From the armature of No. 1 motor the current will flow through lead A' to the contact-bar 4 on the reversing-switch, through lead 19 and, the controller 5 being in the open position, as shown, through lead R⁵, resistance devices R, lead BR', contact-bar 29 on the braking-switch to F' M and F² M through the fields of both motors, from the field of No. 1 motor, through lead 10 E' M, contact-bar 33 on the braking-switch and lead G to the coils H of the magnetic brake device, and from the field of No. 2 motor through the lead G to the coils H of the magnetic brake device. From the magnetic 15 brake device the current flows through the lead BC, arm 31 on the braking-switch, leads F' C and F² C, through the contact-bars 3 and 1, respectively, on the reversing-switch, and through leads AA' and AA² to the armatures 20 of motors No. 1 and No. 2, respectively. From the armature of No. 2 motor the current flows in the direction indicated by the dotted arrow through lead A², contact-bar 2 on the reversing-switch, lead 15, contact-bar 32 on the 25 braking-switch, and to lead R⁵, where it joins with the current from the armature of No. 1 in the branch leading to the resistance devices R, and this united current then flows through lead B R' and over the same 30 course as above described in referring to the current from the armature of motor No. 1. After the braking-switch has been thrown to the position shown in Fig. 2, the braking-current may be controlled by moving the running 35 controller so as to make contact between the terminal points R' R² R³ R⁴ R⁵ of the resistance devices and the contact-bars 14, 14^a, 16, 17, and 18, as may be desired, by precisely the same movements of the controller-handle as in running. It will be seen that 40 with the construction shown the brakes will be applied when the braking-switch is moved to the position shown in Fig. 2, regardless of the position of the running controller, the 45 position of the controller affecting only the quantity of the resistance in the circuit, and the application of the brakes will not be affected by the position of the reversing-switch if it be in position for going ahead or backing. This will be clear from an inspection 50 of the drawings, the contact-bars 1 2 3 4 of the reversing-switch being supposed to occupy a position to make contact with the terminal points F² AA², &c., when the car is running forward, and the points 5, 6, 7, 8, 9, 10, 55 11, and 12 being in a position to make contact with the terminal points F² AA², &c., when the reversing-switch is turned to the position for backing. The contact-points 5 to 12 are alternately connected, so that when 60 they are in contact with the terminal points F² AA², &c., the current will flow from points

19 and 15 to leads AA' and AA², respectively, instead of to leads A' and A² as it does when the reversing-switch is in the forward position, 70 and thus the direction of the current through the armatures of the motors is reversed and the car will run backward. If the brake-switch is now thrown to the position shown in Fig. 2, the controller being in the open position, the current from the armature of No. 1 motor will flow through lead AA' to contact-points 10 and 12 on the reversing-switch through lead 19 and lead R⁵ to the resistance devices. From the armature of motor No. 2 80 the current flows through lead AA² to contact-points 6 and 8 on the reversing-switch, lead 15, contact-bar 32 on the brake-switch, and to lead R⁵, where it joins the current from the armature of No. 1 motor. The combined current then flows through the resistance devices R to lead BR', contact-bar 29 on the reversing-switch to F' M, and F² M through the fields of both motors. From the field of No. 1 motor the current then flows 85 through lead E' M, contact-bar 33 on the braking-switch, and lead G to the coils H of the magnetic brake device, and from the field of No. 2 motor the current flows through lead G to the coils H of the magnetic brake device. 90 From the coils H the current then flows through the lead BC, contact-bar 31 on the braking-switch, lead F' C to contact-points 9 and 10, and lead F² C to contact-points 5 and 7 on the reversing-switch and then through 100 leads A' and A² to the armatures of motors Nos. 1 and 2, respectively. It will thus be seen that the brakes may be applied equally well by the brake-switch when the reversing-switch is set either for running forward or 105 for running backward.

The brake-switch is wholly independent of the reversing-switch and may be thrown at any time without moving or interfering in any way with the reversing-switch. The connections of the brake-switch are such as to direct the current through the field-coils of the motors always in the same direction, whether the brake-switch is set for running or braking. In this way the residual magnetism is not lost at the time the brake-switch is thrown, but will be built up and increased, producing a stronger field and more current. The reversing-switch is so connected as to reverse the direction of the current through 110 the armatures of the motors, but does not affect the direction of the current through the fields of the motors. 115

In Fig. 3 of the drawings I have shown means by which the braking-switch may be 120 operated from either end of the car. A vertical shaft 35 at each end of the car is provided at its upper end with a crank-arm 36 and handle 37 in position to be operated by the motorman, and at its lower end with an arm 38, 125 which is connected by means of a rod 39 with a bar 40 on one end of the central shaft 41 of the braking-switch, which is inclosed in the casing 42. A spring 43, secured to the bar 130

40, tends to hold the bar in the position shown, which corresponds to the running position of the braking-switch, as shown in Fig. 1. When it is desired to apply the brakes, the motor-
 5 man moves the handle to the position in which the pawl 44 may engage with a shoulder or projection 45 on a collar secured to the shaft 35 so as to lock the switch in position. Each of the rods 39 is loosely connected with the
 10 bar 40, so that when the switch is operated from either end of the car the connection of the bar with the other rod will not interfere with its movement. When the switch is to be returned to the running position, the pawl
 15 is released, and the spring 43 pulls the bar 40 back to the position shown.

I claim as my invention and desire to secure by Letters Patent—

1. In an electric-brake system for railway-
 20 cars, the combination with an electric circuit for braking purposes of a running controller, a braking-switch, and means whereby the braking-switch may be operated from either end of the car to cut off the supply of current
 25 from the main line to the controller and apply the brakes when the running controller is in any position.

2. In an electric-brake system for railway-cars, the combination with an electric circuit
 30 for braking purposes of a running controller, a braking-switch, and means whereby the braking-switch may be operated from either end of the car to cut off the supply of current from the main line to the controller and apply the brakes by a single movement of the
 35 braking-switch when the running controller is in any position.

3. In an electric-brake system for railway-cars, the combination, on a car, of a running
 40 controller for each end of the car, and a single braking-switch adapted to cutoff the supply of current from either controller and apply the brakes.

4. In an electric-brake system for railway-
 45 cars, the combination, on a car, of a running controller for each end of the car, and a single
 50 braking-switch adapted to cut off the supply of current from either controller and apply the brakes by a single movement of the
 55 braking-switch.

5. In an electric-brake system for railway-cars, the combination, on a car, of a running controller for each end of the car, and a single
 60 braking-switch, operative from either end of the car, and adapted to cut off the supply of current from either controller and apply the
 65 brakes.

6. In an electric-brake system for railway-cars, the combination, on a car, of a running controller for each end of the car, and a single
 65 braking-switch, operative from either end of the car, and adapted to cut off the supply of

current from either controller and apply the brakes by a single movement of the braking-switch.

65

7. In an electric-brake system for railway-cars, the combination, on a car, of a running controller for each end of the car, and a single
 70 braking-switch adapted to apply the brakes and to connect the running controller in the
 75 braking-circuit.

8. In an electric-brake system for railway-cars, the combination, on a car, of a running controller for each end of the car, and a single
 75 braking-switch adapted to apply the brakes by a single movement and to connect the running controller in the braking-circuit, where-
 80 by the running controller may by its move-
 85 ment vary the resistance in the braking-cir-
 90 cuit and control the brakes.

9. In an electric-brake system for railway-cars, the combination, on a car, of a running controller for each end of the car, and a braking-
 85 switch adapted to apply the brakes and to so connect the running controllers with the
 90 braking-circuit that either controller may by its movement vary the resistance in the
 95 braking-circuit and control the brakes.

10. In an electric-brake system for railway-cars, the combination, on a car, of a running
 90 controller for each end of the car, and a single
 95 braking-switch adapted by a single movement to cut off the supply of current to the controllers and to connect both controllers in a
 100 local braking-circuit with the car motor or
 105 motors, whereby either controller may vary the resistance in the braking-circuit and con-
 110 trol the brakes.

11. In an electric-brake system for railway-cars, the combination, on a car, of a running
 100 controller, a reversing-switch, a braking-
 105 switch independent of the reversing-switch,
 110 an operating device at each end of the car
 115 and connections from the operating devices to the braking-switch whereby the switch
 120 may be operated from either end of the car to apply the brakes.

12. In an electric-brake system for railway-cars, the combination, on a car, of a running
 110 controller at each end of the car, a braking-
 115 switch, an operating-shaft at each end of the
 120 car, and a loose connection from each of the
 125 operating-shafts to the shaft of the braking-
 130 switch, whereby the braking-switch may be
 135 operated from either end of the car to apply
 140 the brakes by a single movement and by the
 145 same movement connect the controllers with
 150 the braking-circuit.

In testimony whereof I have hereunto set
 my hand.

FRANK C. NEWELL.
